Primary Examiner — John Windmuller

Assistant Examiner — Steven Czyz

(74) *Attorney, Agent, or Firm* — Calfee Halter & Griswold, LLP

(57) **CLAIM**

I claim the ornamental design for mat, as shown and described.

DESCRIPTION

FIG. 1 is a front/left/top perspective view of a first embodiment of the mat;

FIG. 2 is a rear/right/bottom perspective view thereof;

FIG. 3 is a front elevational view thereof;

FIG. 4 is a rear elevational view thereof;

FIG. 5 is a right side elevational view thereof;

FIG. 6 is a right side elevational view thereof;

FIG. 7 is a top plan view thereof; and

FIG. 8 is a bottom plan view thereof;

FIG. 9 is a front/left/top perspective view of a second embodiment of the mat;

FIG. 10 is a rear/right/bottom perspective view thereof;

FIG. 11 is a front elevational view thereof;

FIG. 12 is a rear elevational view thereof;

FIG. 13 is a right side elevational view thereof;

FIG. 14 is a right side elevational view thereof;

FIG. 15 is a top plan view thereof; and,

FIG. 16 is a bottom plan view thereof.
